UNITED STATES PATENT OFFICE.

ALFRED JAMES HOLLADAY, OF LONDON, ENGLAND.

DESIGN FOR A TOY.

45,531.

Specification for Design.

Patented Mar. 31, 1914.

Application filed January 29, 1914. Serial No. 815,315. Term of patent 3½ years.

To all whom it may concern:

Be it known that I, ALFRED JAMES HOLLADAY, a subject of the King of Great Britain, residing at London, England, have invented a new, original, and ornamental Design for a Toy, of which the following is a specification, reference being made to the accompanying drawing, forming part thereof.

The figure is a front view of a toy showing my new design.

I claim:

The ornamental design for a toy as shown.

ALFRED JAMES HOLLADAY.

Witnesses:

O. J. WORTH,

R. J. WILLIAMS.
